FLUORESCENT LAMP HOLDER

Adolf G. Mueller and John M. Pistey, Fairfield, Conn., assignors to General Electric Company, a corporation of New York

Application December 10, 1940, Serial No. 369,414

1 Claim. (Cl. 173—328)

Our invention relates to lampholders and more particularly to lampholders of the type adapted to support tubular electric lamps, for example, fluorescent lamps of the type now in commercial use.

It is an object of our invention to provide an improved form of lampholder for fluorescent lamps which is particularly adapted to support the lamp while the lampholder is in inverted position.

It is a further object of our invention to provide a locking means for securing a tubular electric lamp on a lampholder so arranged that there is no danger of the lamp becoming inadvertently dislodged therefrom by jars or vibrations.

In the accompanying drawing Fig. 1 is a view showing a tubular lamp locked in position on lampholders mounted in inverted position; Fig. 2 is a plan view of the lampholder and locking means; Fig. 3 is a side view of the lampholder and locking means showing a lamp in position, and Fig. 4 is a perspective view of the locking means.

Referring to the drawing, Fig. 1 shows a tubular fluorescent lamp 10 supported at each end by a lampholder 11 secured to a supporting surface 12 which may form part of a reflector surface. The lampholders 11 are illustrated, by way of example, as of the type described in a copending application of Frank C. De Reamer and Adolf G. Mueller, Serial No. 274,202, filed May 17, 1939, assigned to the same assignee as the instant application.

This lampholder includes a body of insulating material formed in one face thereof with spaced parallel slots 13 which extend to an edge of the body to receive the spaced prongs of a fluorescent lamp. Within the slots 13 are disposed contact members 14 which support the lamp on the lampholder and make electrical contact therewith. Electrical connection between the wiring system and the contact members 14 is effected by means of terminal screws 15. The outer ends of the contact members 14 are provided with curved surfaces which closely engage the contact pins of the lamp and hold them in seated position within the slots 13.

As long as the lampholders are mounted in upright position on a support, such as a reflecting surface, there is no question but that the curved ends of the contact members 14 will maintain the prongs of the fluorescent lamp within the slots so that the fluorescent lamp is securely mounted in position. In some cases, however, it is desirable to mount the lampholders in inverted

position; for example, when the lamps are suspended from the ceiling of a room. This is the arrangement shown by Fig. 1. Usually, in such situations the spring-biasing action of the curved ends of the contact members 14 is sufficient to prevent the lamp from falling out of the lampholder. However, if the lighting fixture is placed in a position where it is likely to be subjected to jars or vibrations, additional means may be necessary to lock the ends of the lamp within the holders.

To this end, we provide a locking arrangement which, in the instant case, comprises a loop or bail of wire 17 which passes around the outer periphery of the lamp and secures it in position on the lampholder. The ends 18 of the bail extend laterally backwardly from the looped portion from the point at which they engage the periphery of the lamp to a point adjacent the body of the lampholder where their ends are bent inwardly, as shown at 19, to form pivots which are positioned within recesses 20 formed in opposite side walls of the lampholder. The laterally extending opposite ends 18 of the bail rest in grooves 21 formed in the side walls of the holder adjacent the recesses 20. The loop 17 is spring biased so that the lateral portions 18 normally rest in the grooves 21 to hold the locking means in position with the loop engaging the perimeter of the lamp.

In order to release the bail from engagement with the lamp, the opposite lateral ends 18 are flexed or sprung outwardly to release them from engagement with the grooves 21 so that the bail 17 may be swung downwardly about the pivots 19 out of the plane of the lamp to permit the lamp to be released from the lampholder.

Our invention provides an efficient and effective manner of locking a lamp in position on the lampholders so that there is absolutely no danger of the lamp becoming accidentally dislodged therefrom. The arrangement is one which may be applied to lampholders mounting the lamp in a manner other than by seating of the lamp prongs in parallel slots. No structural changes in the interior of the lampholder are necessary to utilize our invention; it is simply necessary to mount the lamp in position on the interior of the lampholder body. The curved bail 17 follows the contour of the lamp and presents an appearance which is pleasing and which does not interfere with the lighting efficiency of the lamp since it is disposed at the ends of the lamp immediately adjacent the holders.

What we claim as new and desire to secure by Letters Patent of the United States is:

In combination, a lamp holder having a body provided with spaced contact members for engaging the spaced contact prongs of a fluorescent lamp, and a bail having opposite ends pivotally mounted on opposite sides of the body of the lamp holder and having a portion adapted to extend over and engage the outer periphery of

the lamp for retaining it in position on the lamp holder, the opposite sides of the body being formed with grooves and the opposite ends of the ball being spring biased into seated position in said grooves to hold the ball in lamp engaging position.
